UNITED STATES PATENT OFFICE.

EMIL A. HIRNER, OF ALLENSTOWN, PENNSYLVANIA, ASSIGNOR TO NOVELTY HOSIERY COMPANY, A CORPORATION OF PENNSYLVANIA.

VERTICALLY-STRIPED SEAMLESS HOSIERY.

1,062,910.

Specification of Letters Patent. Patented May 27, 1913.

Application filed March 22, 1907. Serial No. 363,872.

To all whom it may concern:

Be it known that I, EMIL A. HIRNER, of Allentown, in the county of Lehigh and State of Pennsylvania, have invented certain new and useful Improvements in Vertically-Striped Seamless Hosiery, whereof the following is a specification, reference being had to the accompanying drawings.

My invention relates to the striping or analogous figuring of seamless hosiery, wherein the entire tubular portion of the stocking is knit by a continuous rotary motion, with insertion of heel and toe pockets by reciprocatory knitting, the stocking or sock thus produced being without any sewed seam except the looping required to close the toe pocket. Such hosiery is knit upon a special type of small circular movable needle machine, well known in the art as the circular stocking knitter. The production of vertically striped fabric under the limitations of these machines involves problems quite different from those which have heretofore been solved in the production of striped knit fabric upon flat knitting machines, or other types of machines on which knit webbing may be produced from which fashioned hosiery may be made by seaming. Also the resulting product is structurally different and is commercially a different article from striped seamed hosiery.

In striping seamless hosiery recourse has been had to the rapid alternation of two threads coincidently course after course in such a way as to produce continuous vertical stripes knit always with one thread, while the other thread is "floated" or passed across the back of the knitting during this interval. The objection to hosiery thus produced is that the entire interior of the stocking is filled with a mass or "scaffold" of float threads, which are objectionable in appearance, troublesome when the stocking is being put on, and even if cut off by a special operation after the stocking is knit, present on the inside of the stocking loose ends which are untidy in appearance. If these floats are not cut, the stocking is useless because of lack of lateral elasticity. The primary reason for making hosiery of knit fabric is because of the great lateral elasticity of such fabric, but if threads are floated straight across the back, the fabric is entirely deprived of its elasticity. In order to

avoid these floats I produce vertical stripes in seamless hosiery by a plating operation. Plating is a well known method of knitting by which two threads are fed to the needles simultaneously, but in such relation to each other that one constantly passes to the face of the knitting and appears there, while the other passes to the back of the knitting. The thread which lies upon the face of the fabric is called the plating yarn, and the other the body yarn. The ideal vertically striped seamless stocking would be one in which stripes are formed by the regular coincident inversion of the plating yarn and body yarn course after course at intervals corresponding to the width of the stripes to be produced, but practical difficulties involved in the production of such a striped stocking have not yet been solved, and so far as I am aware no such *seamless* stocking has been produced. As a practical substitute for this I produce striped *seamless* hosiery in which alternate stripes consist of plated knitting, while narrow intermediate stripes are formed by knitting with the body thread only, forming wales of plain knitting, where the plating thread is floated on the back of the fabric. Such hosiery would, to a considerable extent, be subject to the disadvantages of the method of striping which I first described, if the floats were considerable in extent, but by the process of knitting which I have discovered and which I will describe, I am able to produce striped hosiery of this type in which broad stripes, constituting a ground work fabric formed by plating, alternate with narrow stripes (say one, two or three wales) in which the body thread is knit alone while the plating thread is floated. A float thread of two or three wales interval on the inside of the stocking is very insignificant in appearance, occasions no trouble in putting on the stocking, does not materially interfere with the lateral elasticity of the fabric and is otherwise entirely unobjectionable, and I therefore secure by my invention striped seamless hosiery having no objectionable float threads on the interior of the stocking.

It will be noted that the underlying plan involved in the production of hosiery according to this invention, is based upon my discovery that in any one course the aggregate width of the wales of plated knitting

must be so great in proportion to the aggregate width of the wales of plain knitting across which the plating thread is floated, as to maintain without substantial impairment the lateral elasticity of the stocking, and that within the limitations of this plan a large and pleasing variety of striping can be produced.

I am aware that knit fabric has heretofore been produced containing vertical stripes formed by the alternation of wales of plated knitting with other wales across which the plating thread is floated, for example as shown in German Patent No. 10 44,174, to Max Stephan, but as heretofore produced such fabric has embodied stripes produced by floating the plating thread, which are as broad or broader than those produced by the plating of the two threads. 15 20 Under these circumstances the fabric thus produced is so inelastic that such fabric not only never has been, but could not be practically employed in the manufacture of a stocking; and so far as I am aware, no such 25 laterally elastic vertically striped plated fabric with short floats as employed by me has ever been produced for any purpose.

A problem which it was necessary for me to solve in order to secure this product was 30 to produce the short floats within the limitations of a stocking knitter. To produce these the plating yarn must knit for a certain number of needles, then skip one or two needles, and be again thrown into the knitting. 35 No difficulty is involved in an ordinary circular latch needle machine in so manipulating the needles as to withdraw a thread from the knitting for a series of needles and then return it to the knitting provided the interval be not too short; but owing 40 to limitations which are well known to practical knitters, it is difficult to cause a thread to skip one or two needles only for it involves the thread pursuing a zig zag 45 course among the needles, which in a stocking knitter is difficult to secure. By the process of knitting which I will now describe I have accomplished the result of producing perfect laterally elastic seamless 50 striped hosiery, without noticeable or objectionable floats, with broad plated stripes alternating with narrow unplated stripes where the body yarn only is knit while the plating yarn is floated.

55 In the accompanying drawings, Figure I, represents diagrammatically seamless half-hose embodying my invention in a simple form in which the narrow two-wale stripes are formed at equal distances around the 60 tubular web. Fig. II, is a diagrammatic section along the line II, II, of Fig. I. Fig. III, shows in enlarged scale a piece of knit webbing illustrating the formation of the stripes in Fig. I. Fig. IV, represents seamless half-hose knit upon the same general

plan with the variation that certain of the stripes are three-wale stripes and others are one-wale stripes. Fig. V, is a section along the line V, V, of Fig. IV. Fig. VI, is an enlarged view of a piece of the tubular web 70 to illustrate the formation of the stripe. Fig. VII, illustrates hosiery in which the method of striping which I am now describing is employed, not for the purpose of producing striped hosiery in the ordinary 75 use of the term, but for the purpose of producing two narrow and limited stripes, one on either side of the leg portion of the stocking, which simulate the ordinary embroidered "clock". Fig. VIII, is a section along 80 the line VIII, VIII, in Fig. II. Fig. IX, is an enlarged illustration of a piece of a tubular web to illustrate the formation of the "clock." Fig. X, is a diagrammatic development of the positions of the needles 85 and threads as operated according to my process of knitting for the production of striped hosiery. Fig. XI, is a plan view on an enlarged scale of a small portion of the circle of needles on which my invention is 90 practised showing how I am able to manipulate them to produce the short floats. Figs. XII, and XIII, are similar enlarged views of the needles as they are operated in practising my process. 95

Referring to Fig. I, it will be seen that I have there illustrated an ordinary seamless stocking of the type known as "half hose". The stocking is produced with a ribbed top 1, a leg portion 2, formed by continuous rotary knitting, a heel pocket 3, formed by reciprocatory knitting and fashioned in the usual way, a foot portion 4, and toe pocket 5, formed as is the heel pocket 3, and looped to the top of the foot along the line 6. It is a structural peculiarity of seamless hosiery that, although the thread may be changed or reinforced as the knitting proceeds, yet it is possible to knit the entire stocking (omitting the ribbed top), from a single continuous or unbroken thread, the change from circular to reciprocatory knitting and back again not necessarily involving any change in or break of the thread. The stocking shown in the drawing may, 110 therefore, be considered as formed of a single body yarn 10, and in the diagrammatic section which forms Fig. II, the continuous operation of this thread is indicated by the unbroken circle 10. A second or 120 plating thread 11, is employed in practising my invention, being plated with the body yarn for the production of the broad stripes 12, and floated behind the body yarn for the production of the narrow stripes 13. 125 This appears in Fig. II, outside the yarn 10, for the broad stripes, and inside it for the narrow stripes, which device however, is merely a conventional way of illustrating what is more clearly shown in Fig. III, 130

where the position of the yarns is more accurately depicted showing that in the broad stripes the plating yarn is knit with but lies over the body yarn so as to be visible upon the face of the fabric, while for the narrow stripes it passes out of the knitting and runs invisibly behind the body yarn in the form of short floats 15. I will now describe the process of knitting by which I have accomplished this result.

10 In knitting with latch needles the series of needles are caused to successively move up and down with a wave-like motion under the influence of cams acting upon the needles, but the means by which the needles 15 are caused to thus operate have nothing to do with my process. As a means of accomplishing the result which I have described, two additional factors are introduced, first, 20 certain of the needles corresponding in position to the narrow stripes, are withheld from the temporary advance which is given to all the other needles prior to their stitch-forming depression, and second, the plating thread is fed to the needles in advance of 25 the point where the body thread is fed and at a flatter angle. As a result the threads and needles occupy the positions in relation to each other during the knitting operation indicated in Fig. X. In this diagram the ordinary needles 20 at the left of the drawing have advanced to the thread receiving level. They are depressed by the stitch cams along the lines 22, and 23, to 30 form the stitch. They are again advanced to the normal level along the line 24. On the other hand, the needles 25, by which the narrow stripes are to be formed (which I will call the special needles), do not receive 35 the preliminary advance, but enter the knitting operation at a level represented by the dotted line 26, which reaches a point where all of the needles act in unison about in the middle of the stitch forming descent of the 40 other needles.

45 The plating yarn 30, is fed at the point 31, passing under the hooks of the needles and ultimately entering the knit web at the point 32. At the point where this thread is fed to the needle the special needles 25, are depressed below it and consequently they do not receive the plating yarn under their hooks. Furthermore, this point 31 for the feeding of the plating yarn is far enough in advance of the knitting to allow 55 the plating yarn to be wrapped tightly against the upright inner edge of the hook of each of the ordinary needles, before they are brought in line with the special needles. 60 Consequently, when the plating yarn reaches the gap or space corresponding to the two special needles which have not been advanced, it is drawn tightly across between them so as to form a chord of an arc. At 65 this point two special needles fill the gap

but at a level below the thread. As the other needles descend they carry the plating yarn down with them and owing to the angle at which this yarn passes from its guide and into the knitting it rests against the 70 upright edge of the hook at nearly its thinnest point when the special needles come into contact with it, in consequence of which the curved tops of the hooks of these special needles come into contact with it at a point 75 behind their summit, so that it passes not in front of, but behind the special needles, and the plating yarn never enters the hooks of these latter needles. The body yarn is fed from the point 33 nearer the knitting 80 than the other thread, and enters the knitting in the usual way being received by both sets of needles.

I am aware of the process of knitting which is described in German Patent No. 94,884, to Sturgess. This differs from mine in the relative position in which the plating yarn is fed to the needles and in the order in which the needles are manipulated, the result being that the plating thread lies under the top of the hook of the plating needles as they are drawn down to the level of the other needles, in consequence of which it is difficult to induce the plating thread to always fall behind the non-plating needles. 90

95 In Fig. XI, I have illustrated by plan view the way in which the plating yarn is tightly stretched between the ordinary 100 needles, so as to permit the special needles to pass in front of it. This operation will be the better understood by examining Figs. XII, and XIII. In Fig. XII, one of the ordinary needles 20, carries the plating 105 thread against its shank. A special needle 25, is shown in front of this, somewhat in advance by reason of the circular disposition of the needles. As the needle 20, descends, the plating yarn is held tightly against the 110 shank and as it approaches the top of the hook of the needle 25, it retreats slightly so that at the time the two needles are nearly 115 on the same level, the yarn is in the rear of a point at which the curved top of the special needle would throw the yarn in front of it instead of behind it.

120 In Fig. IV, I have illustrated a stocking constructed upon the same principle as that previously described, but with this variation that certain of the stripes 50, have a breadth of three needles, while the others 51, have a breadth of only one needle, these stripes being in every case formed by knitting the body yarn alone with the plating 125.

yarn floated behind it; all the rest of the stocking being knit with the one yarn plated upon the other.

In Fig. VII, I have illustrated the application of my invention to the formation of a clock upon an otherwise plain seamless stocking. For this purpose there is but one narrow stripe 60, on the side of the leg formed as shown in Fig. IX, by knitting the body thread alone for a single needle. For the accomplishment of this the leg of the stocking is knit with ordinary solid plating until the course is reached which coincides with the upper end of the stripe 60. At this point the two needles which are to form the clocks are caused to operate as the special needles in the diagram Fig. X, causing the formation of the stripes or clocks 60, by the knitting of the body yarn alone with the plating yarn floating behind. When the course is reached where the clock should end, the remainder of the tubular web is knit as ordinary plated work.

It will of course be understood that in this specification the terms "striping" and "vertical-striping" are meant to include analogous figuring even though the succession of the plated and unplated loops, course after course, is not regular as when vertical stripes in the geometrical sense are produced. The phrase "vertical striping" is used in this specification merely in contradistinction to "horizontal striping," which is produced by a change of thread occurring after the knitting of one or more complete courses, a process of knitting which has

nothing in common with the process by which the hosiery described in this application is produced.

Having thus described my invention, I claim:

1. A vertically striped seamless stocking composed of stripes of plated knitting, alternating with stripes of plain knitting where the plating thread is floated at the back, the aggregate width of the stripes of the plated knitting being so great, in proportion to the aggregate width of the stripes of plain knitting, as to maintain the lateral elasticity of the stocking substantially un- 50 impaired.

2. A seamless circular knit stocking ornamented by figurings of contrasting colors, wherein the groundwork fabric is of plated knitting consisting of a body yarn knit with a contrasting plating yarn on the face, and wherein the figures consist of plain knitting of the body yarn only with the plating yarn floated behind said figures, and wherein the whole number of wales of ground-work in any one course so much exceeds the whole number of wales in the figures as to maintain the lateral elasticity of the stocking substantially unimpaired. 55

In testimony whereof, I have hereunto signed my name, at Allentown, Pennsylvania, this twentieth day of March, 1907.

EMIL A. HIRNER.
